UNITED STATES PATENT OFFICE

2,625,105

SELF-REVERSING ROTARY PUMP

Louis Fincher, Lufkin, Tex.

Application June 10, 1949, Serial No. 98,287

5 Claims. (Cl. 103—3)

1

This invention relates to a self-reversing pump in which the direction of fluid flow therethrough is reversed upon each revolution of the inner housing of the pump. It is an object of this invention to provide a pump of this class which may be employed in a pumping unit employed in pumping fluid from wells, as oil wells.

It is a further object of this invention to provide a pump of this class which delivers fluid into, and takes fluid from, the cylinder of such a pumping unit to actuate the piston therein.

It is an object of this invention to provide a pump of this class in which the inner housing is driven from the same shaft as the impeller and at a different rate of speed.

It is a further object of this invention to provide a pump of this class in which the direction of flow of fluid therethrough is reversed by virtue of the relative rotation between the inner housing and the impeller.

It is a further object of this invention to provide a pump of this class in which deceleration at the end of the stroke is obtained by the building up of fluid pressure operable within the inner housing.

It is a further object of this invention to provide a pump of this class in which acceleration is obtained by the gradual increase of port communication between the inner housing and the outer housing as the return stroke commences.

It is still a further object of this invention to provide a pump of this class in which a valve operates within an inner housing passage to bypass fluid to circulate exclusively within the inner housing at substantially the end of a piston stroke.

It is a further object of this invention to provide a pump of this class which is adapted to deliver more fluid when discharging in one direction than it delivers when reversed and discharging in the opposite direction.

It is still a further object of this invention to provide a pump of this class which delivers more fluid when discharging in one direction than when discharging in the other direction so that a piston travel distance may be adjusted in a cylinder into which the fluid is discharged.

It is also an object of this invention to provide a pump of this class which may be driven to discharge fluid from an outer housing by a rotatable pump within a rotatable inner housing, such rotatable pump being any type of conventional pump as either an exterior or interior gear type pump, a cam type pump, a radial plunger pump, or a vane type pump.

2

It is a further object of this invention to provide a pump of this class which has an outer housing provided with an adjustable boss by which the pump may be regulated to discharge more fluid in one direction than in the opposite direction.

It is a further object of this invention to provide a pump of this class in which the ports in the inner, rotatable housing are larger than the bosses on the outer stationary housing so that there is a gradual reversal of direction of flow through the pump; the ports in the rotatable inner housing never being completely closed by the bosses.

15 It is also an object of this invention to provide a pump of this class in which a rotatable inner housing is driven by any type of transmission at a slower rate of speed than is the impeller means within such housing.

20 Other and further objects of this invention will be apparent when the drawings are considered in connection with the specification, in which:

Fig. 1 is a sectional elevation of one embodiment of the invention taken along line 1—1 of Figs. 2 and 3;

Fig. 2 is a sectional elevation taken along line 2—2 of Fig. 1;

Fig. 3 is a sectional plan view taken along line 3—3 of Fig. 1;

Fig. 4 is a sectional elevation taken along line 4—4 of Fig. 2;

Figs. 5, 6, and 7 are sectional elevations, and also diagrammatic views illustrating the flow of fluid through the pump; these figures being taken along line 1—1 of Fig. 2;

Fig. 8 is a sectional elevation of another embodiment of the invention;

Figs. 9, 10 and 11 are sectional elevations, and also diagrammatic views illustrating the flow of fluid through the pump; these figures being views taken along line 9—9 of Fig. 8;

Fig. 12 is an elevation showing the pump of this invention employed to actuate a piston in the power cylinder of an oil well pumping unit; and

Fig. 13 is a plan view taken along line 13—13 of Fig. 12.

The pump has an outer housing 1 of non-circular cross-section, such cross-section amounting to substantially an oval or an ellipse. This housing has fluid connections 2 and 3 on diametrically opposed sides thereof and which has a shaft 4 journaled in the outer housing 1, the axis of which passes substantially transversely of the axis through the connections 2 and 3. Bosses 5

and 6 extend radially inwardly from the outer housing and have surfaces 7 and 8 which form arcs of a circle centered at the shaft axis. The inner housing 15 is mounted, as will be herein-after described, with axis substantially perpendicular to the common axis through the fluid connections 2 and 3, and substantially centrally thereinbetween. As the inner housing is substantially circular in cross-section, a substantially crescent shaped space is provided on either side of the bosses 5 and 6 with the crescent tips adjacent the bosses. Thus structures which may be termed slots 9 and 10 are formed in the housing to communicate with connection 2, and extend in decreasingly tapered size inwardly to terminate at the bosses 5 and 6. Also, slots 11 and 12 are formed in the housing 1 and extend from connection 3 in decreasingly tapered size to terminate at the bosses 5 and 6.

An inner housing 15 is mounted on the shaft 4 and has an opening 16 therein which eccentrically surrounds the impeller 17, which is also mounted on the shaft 4; the impeller 17 being of the vane type with vanes 18 operable in slots 19, which are radially spaced from the impeller and shaft axes, which axes are in coincidence. Ports 21 and 22 in the inner housing 15 open outwardly through the housing periphery and communicate inwardly with the opening 16.

The inner housing 15 has a cored passage 23 therethrough on one side thereof, which extends in arcuate shape of irregular cross-section between the port 21 and the port 22. As shown in Figures 2 and 3, the inner housing has a threaded hole 24 through the side thereof to receive the bushing 26, which has a central bore 27 therein in which the stem 28 of the valve 29 reciprocates. The spring 30 is based in an annular groove 31 in the bushing 26 and bears against the valve 29 to seat it upon the valve seat 32, which is located substantially centrally of the passage 23.

The end plate 35 at one end retains the inner housing 15 within the outer housing 1. At one end the shaft 4 is rotatable within the bearing unit 36 located in the end plate 35, and at the other end it is rotatable within the bearing unit 37 located within the end plate 38. Both end plates 35 and 38 are connected to the main body of the housing 1 by means of the bolts 39. A retaining cap 41 has a seal 42 therein and is connected to end plate 38 to complete the enclosure at the end through which the shaft passes for connection to a driving means. At the other end of the pump enclosure is completed by the flange or closure cap 40 which is connected to the end plate 35.

An internal gear 43 is pressed within the housing 1 and rigidly located therein, and a gear 44 is keyed to the shaft 4 to mesh with an idler 45 which is interposed between the internal gear 43 and the gear 44.

The gear 45 has the bushing 58 therein, and this establishes the rotative surface between the gear and the pin 47, which is rigidly pressed into the flange 48. This flange 48 has the bushing 49 pressed therein as the bearing member to establish its rotative surface about the shaft 4, and the flange 48 also has the gear 50 firmly pressed thereon.

The gear 50 meshes with the idler 51, which has pressed therein the bushing 59 to establish its rotative surface about the pin 52, which is pressed within the flange plate 53, which in turn is rigidly connected to the inner housing 15 by means of machine screws 54. This location of

the idler 51 places it in mesh with the internal gear 56, which is rigidly pressed into the housing 1. The flange 53 has the bushing 55 therein, which establishes its rotative surface about the shaft 4.

By virtue of this transmission, the impeller 17, which is rigidly connected to the shaft 4, and which is driven thereby, may be driven at the speed of rotation of the shaft, whereas the inner housing 15 may be driven at a different speed, which is shown in the disclosure of this invention as being at a slower than shaft speed.

Assume the direction of rotation of the shaft 4 to be as indicated by the arrows in Figures 5, 15 6 and 7. Then when the elements are in position shown in Fig. 5, fluid is passing into the pump through the connection 2 and is being transferred by the impeller 15 to pass out the connection 3. The connections 2 and 3 may be connected, for purposes of illustration, to the 20 ends of a cylinder which encloses a piston. In this condition the valve 29 is seated within the passage 23.

As rotation continues, the inner housing 15 25 moves toward the position shown in Fig. 6 and slowly decreases the communication between the connection 2 and the port 21. The slot 9 being tapered toward the boss 5, reduces the area of passage of fluid between the outer housing 1 and the inner housing 15, and an excessive pressure is built up within the inner housing. The flow of fluid out the connection 3 to operate the piston of the hydraulic cylinder to which this connection leads, is substantially decreased as this 30 condition develops; and consequently the speed of the piston operation is appreciably decelerated. Finally the edge 61 of the port 21 comes into communication with the surface 7 of the boss 5 and completely closes off the passage of fluid between connection 2 and the inner housing 35 40.

The pressures built up within the inner housing result in the lifting of the valve 29 so that the fluid entrapped within the inner housing flows around therein in a substantially circular path following the course of the port 21, the opening 16 of the impeller, the port 22, and through the passage 23 past the valve 29 and back to the port 21.

As the rotation continues, the edge 60 of the port 22 passes into communication with the slot 10 and the fluid, by virtue of the position of the impeller, as shown in Fig. 6, begins to circulate back out through the connection 2, and the diminishing of the excess pressures within the inner housing 15 results in the seating of the valve 29 to cut off flow through the passage 23. Then as the port 22 rotates into communication with the wider portions of the slot 10, there is a gradual increase of fluid, which is discharged through the connection 2, and consequently a gradual increase of the piston speed now on the opposite stroke. This volume of fluid and consequent speed of piston reach their maximum when the elements of the pump are in the position shown in Fig. 7.

It is obvious that the operation of this pump is susceptible to an infinite number of modifications, as the relative speed between impeller rotation and inner housing rotation may be varied, as by substituting a variable speed reducer system for the gear reduction system shown in Fig. 2. The operation of this pump may be varied by adjusting the bushing 26 against the spring 30 to regulate its tension so as to vary

the lifting point of the valve 29. The pump may also be designed for various conditions of operation by varying the shape of the slots and the bosses of the outer housing. Variation may also be obtained by varying the eccentricity of the opening 16 with relation to the shaft axis.

In the embodiment of the invention disclosed in Figs. 8-11, the structural relation of outer and inner housings is similar to that shown in Figs. 1-7. However, in such embodiment, the outer housing 10 includes a closure plug 71 which has threaded holes 72 therein. A boss 73 is provided which has bored and counterbored holes 74 therein so that the boss may be adjustably positioned at any of several points on the closure plug by means of the screws 75. An inner housing 16 is mounted on the backing plate 11 which is connected to be driven by a transmission, not shown, which is mounted on the shaft 78. This transmission may be of the type disclosed in Figs. 2 and 4, or it may be of any other conventional type as well. The inner housing has opposed ports 79 and 80 therein which are of greater peripheral width than the adjustable boss 73 or the boss 81 which is integrally cast with the outer housing 10.

An impeller means 82 for transferring fluid is mounted on the shaft 78 and in the form of the invention disclosed, this fluid transfer means is of the vane type as also shown in Figs. 1 and 5-7. This impeller rotates with the shaft 78 and at a greater speed than does the inner housing 16 which is driven by the transmission, not shown.

The outer housing 10 has opposed connections 83 and 84 therein with connection axis extending substantially perpendicular to the axis through the bosses 73 and 81. The outer housing also has compartments 85 and 86 therein which are in communication with the slots 87 and 88 respectively. A wall 89 separates the compartments and has the valve seat 90 therein which is controlled by the valve 91. Another valve, not shown, is mounted to control the valve seat 92 in the wall 89, this valve extending oppositely from the valve 91 and opening in the opposite direction in the compartment 85.

The outer housing also has slots 93 and 94 similar to the slots 87 and 88, and all of these slots are tapered in decreasing size toward the bosses 73 and 81.

As shown in Fig. 9, with the impeller 82 and the inner housing 16 rotating in a clockwise direction, fluid enters through the connection 83 and is discharged out through the connection 84. When the inner housing has rotated to a position, shown in Fig. 10, fluid circulates as shown by the arrows; and part of the fluid takes a path through the outer housing, through the port 79 of the inner housing, through the impeller, and out through the port 80 of the inner housing into the outer housing. The other portion of the fluid takes a similar path through the outer housing on the right side of the pump, through the port 79, through the impeller, and out through the port 80 into the outer housing. It should be noticed that in this embodiment of the invention, because the ports 79 and 80 have greater peripheral width than the bosses 81 and 73, the ports are never closed and with this construction the deceleration as the inner housing approaches the position shown in Fig. 10 and the acceleration as it moves away from this position, is much more gradual and imperceptible than in the previously embodiment of the

invention disclosed. As the inner housing 16 and the impeller 82 continue clockwise rotation, the direction of fluid flow is reversed as shown in Fig. 11.

Should it be desired to discharge more fluid through one connection than is discharged through the other connection, it is only necessary to adjust the position of the boss 73. Should the boss be moved to the left hand side of the housing 10 more fluid will be discharged out of the right hand side of the outer housing through the connection 84 than is discharged through the connection 83 on the opposite stroke.

This is obvious since positioning of the boss 73 to the left shortens the length of time the ports 79 or 80, when on the left hand side of the pump, receive fluid through the connection 83, and increases the length of time the ports 79 or 80, when on the right hand side of the pump, discharge fluid out through the connection 84. As the fluid containing space of the inner housing and impeller remains constant, and is constantly filled, it follows that the length of time a port 79 or 80 can discharge in one direction is proportional to the volume of fluid delivered in that direction.

However, should the pump tend to deliver an excess of fluid through the compartment 84 over the amount which may be discharged out therethrough, the excess fluid will circulate into the compartment 85, lift the valve 91 from the seat 90, and recirculate into the left hand side of the compartment. Should the pump tend to discharge more fluid out of the connection 83 than can be received out therethrough, the excess fluid will circulate into the compartment 86, lift a valve, not shown, from the seat 92 and discharge through the compartment 85 and into the right hand side of the pump. This over-load feature is not limited to the form of over-load valve disclosed, but any conventional over-load means may be employed for the purpose.

A method of employing either embodiment of the invention is disclosed in Figs. 12 and 13 in which a self reversing pump, as the pump having the outer housing 10, is mounted in the pumping unit 101 which includes a power cylinder 102 which has a piston, not shown, therein which moves up and down in the power cylinder. This piston is connected to the sucker rods 103 which are connected with the bottom hole pump, not shown, which pumps oil from a well.

The self reversing pump discharges through line 104 into the power cylinder 102 and on the return or down stroke of the piston, it discharges the fluid back through the line 105 into the surge tank 106. A series of valves 107 are provided near the top of the power cylinder 102, all but one of which remain closed. The valve which is open limits the upward travel of the piston within the power cylinder and thereby limits the vertical position at which the plunger of the bottom hole pump, not shown, operates in the well. On the up stroke of the piston within the power cylinder, there is a possibility that an amount of fluid will pass upwardly above the piston into the space between the upper piston end and the top of the power cylinder. When this fluid is brought in contact with that valve 107 which may be open, such fluid is discharged through the line 110 and passes into the reservoir 111 to be picked up by the scavenger pump 112 and discharged in the surge tank 106.

In the pumping unit disclosed, air storage tanks 115 and 116 are kept at desired pressure by means

of the compressor 117, which is driven by the prime mover 118 which also drives the self reversing pump employed. This compressor may be regulated by any type of conventional or novel regulatory means, not shown, which will keep the compressor running whenever necessary to maintain a desired pressure within the air storage tanks. The air from the storage tanks 115 and 116 communicates by means of the line 119, with the top of the surge tank 106, and keeps the fluid therein under a pressure to maintain the pumping unit counter-balanced.

Since it is desirable that the self reversing pump employed discharge more fluid on the power, or up stroke, of the piston within the cylinder 102 than it discharges back into the surge tank on the down stroke, the adjustment obtained by the boss 73 disclosed in the embodiment of the invention shown in Figs. 8-11 is of particular advantage.

The housing 1 is shown threaded at 63 in Fig. 1 to receive a gauge of any conventional design, which is actuated by fluid communication thereto to indicate the position of the piston or element which is actuated by the pump. Such a gauge may be of the conventional type in which the pressure of fluid operates against well known means within the base of the gauge to rotate the indicating dial of the gauge to various positions responsive to various pressures occurring in the gauge operating fluid. As the fluid pressure on the upstroke must be greater, because of the load to be lifted, than the fluid pressure on the downstroke, the dial indication of a higher pressure designates to the observer that the pump is supplying fluid to the power cylinder 102. As the stroke changes, the dial rotates back toward the lowest pressure indication on the gauge face, and then as the downstroke develops the dial indication increases as the pump transfers fluid into the surge tank 106, but does not reach as high an indication as is reached on the power cylinder supplying stroke. In Fig. 2, such a gauge 63' is shown in the threaded bore 63, and such gauge 63' is also shown in Fig. 4.

It is particularly pointed out that this invention is not limited to either of the embodiments hereinabove disclosed but other structures may be employed within the concept of the invention which broadly considers a self reversing pump which is designed to decelerate the speed of a piston or other element operated thereby as the reversal point is approached, and which is designed to accelerate the speed of the piston or device operated by the pump after the reversal point is passed. Any type of fluid transfer means within the inner housing is considered within the scope of the invention and also any type of transmission is considered which will drive the inner housing at a speed different than that of the fluid transfer means which is mounted on the same shaft.

What is claimed is:

1. A self reversing pump to control the flow of an actuating liquid for a well pumping unit comprising, a housing, a flow chamber therethrough, an impeller rotatable in said chamber, a control member surrounding said impeller and constructed to determine the direction of flow of the liquid from said impeller, means supporting said impeller and said member and connected to positively drive said member and at a pre-determined rotational speed ratio relative to said impeller, control ports in said member for the inlet and outlet of liquid relative to said impeller, and means pro-

jecting into said housing from opposite sides thereof and with substantially common axis substantially perpendicular to the axis of said flow chamber to engage said member to divide said chamber into inlet and outlet portions depending upon the position of said member ports.

2. A self-reversing pump to control the flow of an actuating liquid for a well pumping unit, comprising a housing, a flow chamber therethrough, an impeller rotatable in said chamber, a control member surrounding said impeller and constricted to determine the direction of flow of the liquid from said impeller, means supporting said impeller and said member and connected to positively drive said member and at a pre-determined rotational speed ratio relative to said impeller, control ports in said member for the inlet and outlet of liquid relative to said impeller, means projecting into said housing from opposite sides thereof and with substantially common axis substantially perpendicular to the axis of said flow chamber to divide said chamber into inlet and outlet portions depending upon the position of said member ports, a liquid passageway in said control member extending between said ports therein and a valve intermediate the ends of said passageway for opening said passageway when a pre-determined excess liquid pressure is obtained therein on the outlet control port side of said valve to return liquid to the inlet control port side of said valve to reduce said excess pressure and to close when said pressure is reduced to a pre-determined limit.

3. A self-reversing pump to control the flow of an actuating liquid for a well pumping unit comprising, a housing, a flow chamber therethrough, an impeller rotatable in said chamber, a control member surrounding said impeller and constricted to determine the direction of flow of the liquid from said impeller, means supporting said impeller and said member and connected to positively drive said member and at a pre-determined rotational speed ratio relative to said impeller, control ports in said member for the inlet and outlet of liquid relative to said impeller, means projecting into said housing from opposite sides thereof and with substantially common axis substantially perpendicular to the axis of said flow chamber to divide said chamber into inlet and outlet portions depending upon the position of said member port, a liquid passageway in said housing connecting the flow chamber portion outwardly of said projecting means on one side of said projecting means axis with the flow passage portion outwardly of said projecting means on the other side of said projecting means axis, and a valve intermediate the ends of said passageway for opening said passageway when a pre-determined excess liquid pressure is obtained therein on the outlet control port side of said valve to return liquid to the inlet side of said flow chamber to reduce said excess pressure and to close when said pressure is reduced to a pre-determined limit.

4. A self-reversing pump to control the flow of an actuating liquid for a well pumping unit comprising, a housing, a flow chamber therethrough, an impeller rotatable in said chamber, a control member surrounding said impeller and constricted to determine the direction of flow of the liquid from said impeller, means supporting said impeller and said member and connected to positively drive said member and at a predetermined rotational speed ratio relative to said impeller, control ports in said member for the inlet and

outlet of liquid relative to said impeller, means projecting into said housing from opposite sides thereof and with substantially common axis substantially perpendicular to the axis of said flow chamber to divide said chamber into inlet and outlet portions depending upon the position of said member port, a liquid passageway in said housing connecting the flow chamber portion outwardly of said projecting means on one side of said projecting means axis with the flow passage portion outwardly of said projecting means on the other side of said projecting means axis, and a valve intermediate the ends of said passageway for opening said passageway when a predetermined excess liquid pressure is obtained therein on the outlet control port side of said valve to return liquid to the inlet side of said flow chamber to reduce said excess pressure, and to close when said pressure is reduced to a pre-determined limit, the projecting means on at least one side of said housing being movable substantially parallel to the axis of said flow chamber to increase the flow chamber volume on one side of said projecting means axis and to decrease the flow chamber volume on the other side thereof.

5. A self-reversing pump to control the flow of an actuating liquid for a well pumping unit comprising, a housing, a flow chamber therethrough, an impeller rotatable in said chamber, a control member surrounding said impeller and constricted to determine the direction of flow of the liquid from said impeller, means supporting said impeller and said member and connected to positively drive said member and at a predetermined rotational speed ratio relative to said impeller, control ports in said member for the inlet and outlet of liquid relative to said impeller, means

projecting into said housing from opposite sides thereof and with substantially common axis substantially perpendicular to the axis of said flow chamber to divide said chamber into inlet and outlet portions depending upon the position of said member ports, a liquid passageway in said control member extending between said ports therein and a valve intermediate to the ends of said passageway for opening said passageway when a pre-determined excess liquid pressure is obtained therein on the outlet control port side of said valve to return liquid to the inlet control port side of said valve to reduce said excess pressure and to close when said pressure is reduced to a pre-determined limit, the projecting means on at least one side of said housing being movable substantially parallel to the axis of said flow chamber to increase the flow chamber volume on one side of said projecting means axis and to decrease the flow chamber volume on the other side thereof.
